HYPODERMIC INJECTION APPARATUS

George N. Hein, Jr., San Carlos, Calif.

Application November 20, 1951, Serial No. 257,263

10 Claims. (Cl. 128—173)

1

This invention relates to a hypodermic injection apparatus and in its specific aspects aims to provide a mechanism of this character by means of which medicament may be hypodermically injected without the use of a skin-penetrating needle.

It is an object of the invention to furnish an apparatus the parts of which may readily be adjusted and controlled so that the pressure under which the medicament is ejected is varied. Accordingly, the depth of penetration of the tissues will be correspondingly varied.

A further object is that of furnishing a mechanism in which the volume of the dosage to be injected may also be varied at the will of the operator.

Still another object is that of providing a hypodermic injection apparatus which will include relatively few parts, each individually simple and rugged in construction, such parts being capable of ready assemblage to furnish a unitary device operating over long periods of time with freedom from all difficulties.

With these and other objects in mind, reference is had to the attached sheets of drawings illustrating one practical embodiment of the invention and in which:

Fig. 1 is a sectional side view of the apparatus and showing the parts of the same adjusted to one position;

Fig. 2 is a similar view but showing the parts shifted to a different position;

Fig. 3 is a sectional plan view taken along the line 3—3 and in the direction of the arrows as indicated in Fig. 4;

Fig. 4 is a transverse sectional view taken along the line 4—4 and in the direction of the arrows as indicated in Fig. 3;

Fig. 5 is a sectional plan view of a fragment of the operating mechanism and taken along the line 5—5 and in the direction of the arrows as indicated in Fig. 4;

Fig. 6 is a side elevation of the apparatus; and

Fig. 7 is a fragmentary transverse view taken along the line 7—7 and in the direction of the arrows as indicated in Fig. 1.

In these views the numeral 10 indicates a casing of any desired configuration which is hollow and to the forward end of which an extension or nose-piece 11 is secured, as for example, by screw threads. The nose-piece is formed with a bore through which a plunger 12 is projectible into a medicament chamber. For purposes hereinafter brought out this plunger is formed with a passage 13. The medicament chamber may take one of

2

numerous different forms. However, preferably instead of directly receiving liquid medicament it will receive an ampule which contains the desired solution or liquid.

5 Thus, the walls of the chamber may be provided with a lining 14 of suitable material such as rubber. The ampule will embrace a preferably cup-shaped body which is tapered in an outward direction and identified by the numeral 15. This 10 body again is conveniently formed of rubber although other materials might be employed. Its outer end is open and defined by a relatively heavy bead portion 16. A nozzle is provided which includes a base 17 preferably formed with a peripheral groove to receive the inwardly extending bead formed in the edge of flange 16. Beyond this 15 the nozzle is formed with a plate and an outwardly extending tip 19 which is provided with a passage 20 extending throughout its length and the base 20 17. To secure these parts against displacement a loading cap 21 is employed which is formed with a central aperture through which the projecting portion 19 may extend. Conveniently, screw threads or any other suitable form of coupling are 25 furnished between the loading cap and the extension 17 in order to provide for a quick-detachable coupling.

The rear end of stem 12 is connected to or may be integral with an end wall 22 associated with a 30 cylindrical member 23. The latter forms a part of a pressure accumulator structure. It is closed at its rear end by a body 24 which may have screw threaded connection therewith. A flange 25 extends inwardly from the cylindrical body 23 and is 35 disposed beyond an expansible member 26 which has its base flange secured against movement with respect to the assembly. While in certain respects it is preferred to utilize an expansible member of simple design, it will be understood that 40 one of numerous different structures might be employed in lieu of the unit specifically shown at 26.

The forward face of member 24 is conveniently 45 formed with a well 27 in line with the expansible member 26. To the rear of this well the body of member 24 is formed with cylinders 28, 29 and 30. Passages 31 and 32 are provided between the well portion 27 and cylinders 28 and 29 respectively. Within bore 28 a piston 33 is disposed. This 50 piston may form a part of an assembly 35 which includes a thrust bearing 34. Loosely contacting the outer part of this bearing is a threaded stem 36 which engages within a correspondingly threaded opening forming a part of an end cap 55 37 secured to the rear of casing 10. Stem 36 may

terminate in an irregular rear portion such as may conveniently mount the end of a crank (not shown). At a point short of portion 38 a split washer 39 or other part acting as an indicator, may be mounted.

Conveniently a sleeve 40 is secured to or forms a part integral with cap 37. This sleeve is provided with a slot 41 adjacent which indicia indicative of "pressure" may be disposed. As illustrated in Fig. 6 this indicia may include graduation marks. In any event it will be apparent that the edge of washer 39 or its equivalent will be visible through the slot 41 and in cooperation with the indicia will register the position to which stem 36 has been projected or retracted. According to this position a corresponding pressure will exist within cylinder 28 in a manner hereinafter brought out.

Within the bore of cylinder 29 a piston 42 is disposed. This piston involves an assembly again including an anti-friction bearing 43. Conveniently stem 44 may form an integral part of one of the elements of this bearing. In common with stem 36 it has its threads bearing against the threads of an opening formed in cap 37 and is provided with a rearward extension suitable for mounting a crank or wrench. Also, it conveniently mounts a split ring 45 or other suitable indicating element. The latter moves adjacent slot 46 formed in sleeve 40. That slot may have indicia disposed adjacent it which identifies the dosage or volume of the medicament and marks which are indicative of fractions of the entire dosage.

While any suitable packing provision may be associated with pistons 33 and 42 it is preferred that as shown they may be formed with grooves within which are disposed O-rings 48. Split washers 47 may be mounted in each of the bores 28 and 29 adjacent their rear or entrance ends. These washers in cooperation with the rear portions of the piston assemblies will act as limit stops to prevent too great a retraction of the pistons. The forward ends of passages 31 and 32 preferably terminate in grooves 49 extending across the base portion of well 27. These will prevent a "freezing" of the expansible member 26 into contact with the base of the well surface in the event that such member is in effect completely collapsed.

The apparatus is provided with a lock structure to retain against movement the assembly of which tube 23 and member 24 form parts. The lock structure cooperates with the bore of cylinder 30. It is apparent that it might cooperate with other portions to achieve the desired functions. Also, a lock structure different from the one herein shown might be employed. However, it is definitely preferred that an assembly of mechanism of the general type illustrated be utilized. Also, by having the lock extend into bore 30 the device is rendered extremely compact.

Thus, the numeral 50 identifies a transversely shiftable pin which is preferably supported by the thickened walls which form a part of the extension or rearward sleeve 40. This pin is provided with a notch 51. When the parts are in the positions shown in Fig. 5, this notch will permit of a rotation of shaft 52 which is retained against axial displacement in any desired manner. The end of shaft 52 extends beyond the body of the device and mounts an actuating arm or lever 53. A shoulder 54 preferably forms a part of shaft 52 as shown in Fig. 2. This shoulder engages with pin 50 when the latter is in one extreme

position to prevent a rotation of shaft 52. The shaft is notched or cut out to provide a cam portion 55. The latter rides against the outer surface of a head 56 against which the outer end 5 of a spring 57 may bear. That spring may in certain instances be dispensed with. However, ordinarily such a member should cooperate with the head to urge the latter outwardly.

The stem 58 is attached to head 56 and extends into the bore of a slotted spool assembly 59. Also disposed within that bore is a block of relatively soft rubber as indicated at 60 which has its outer edges extending in the form of an arc normally providing a continuation of the spool surfaces. Encircling block 60 is a sleeve 62 also preferably of soft rubber. This sleeve has its bore in engagement with the shank 61 of the spool as well as the side edges of the block 60. Braking elements, preferably in the form of substantially semicircular shoes 63 of metal, encircle sleeve 62. A further set of rotatably offset shoes 64 of similar material encircle shoes 63. Rings of relatively hard rubber 65 may be disposed adjacent opposite ends of the assembly. Also if desired, rings of metal (not shown) may retain the parts of the assembly against displacement with respect to each other.

As is apparent if pin 50 is shifted to a position at which its notch 51 is in line with shoulder 54, then shaft 52 may be turned. Such turning is achieved by means of the actuating lever 53 or its equivalent. When turned from the position shown in Fig. 5 to that illustrated for example in Fig. 2, cam portion 55 will ride against the upper end of head 56 thereby shifting rod or stem 58 inwardly of the spool bore. So shifted it will serve to displace the core block 60 to expand portions of the latter through the sides of the slit of the spool stem 61 into engagement with the inner faces of sleeve 62. The latter will now be expanded to correspondingly expand the shoes 63 and 64. This will cause the outer faces of the latter shoes to frictionally engage with the face of bore 30. So engaged the parts will be held against movement. This will occur because the rear or outer end of spool 59 has threaded engagement with end of cap 37 which is anchored against movement with respect to casing 10.

In use it will be understood that with the parts in the position shown in Fig. 1 an ampule embracing an invertible rubber cup 15 may be positioned within the medicament chamber after which the loading cap 21 is applied to the nose piece of extension 11. As afore brought out ampules of diverse characters may be utilized in lieu of the unit specifically illustrated. In any event at the time of the assembly of the apparatus the interior of the accumulator as defined by tube 23 will have been charged with a compressible gas (for example nitrogen). The pressure value may be on the order of 1,500 pounds to the square inch. Such charging has been achieved by, for example, dismounting plug 67 obstructing passage 13 and introducing gas under pressure through this passage into the interior of the pressure accumulator.

Now assuming that a full or capacity dose of medicament is to be administered under maximum pressures, then an operator will shift pin 50 and rotate shaft 52 in order to prevent movements of member 24 with respect to casing 10. A ratchet or crank will be mounted upon the rear end 38 of stem 36. The latter will be turned until its piston 33 projects into bore 28 to a maxi-

imum extent. So projected liquid within that bore in advance of the piston will be expelled through passage 31 into the body of the expandible member 26. That liquid may take one of numerous different forms including even a relatively heavy grease or oil. The crank or ratchet will be dismounted from the rear portion 38 of stem 36 and will be mounted upon the corresponding portion of stem 44 and turned to rotate the latter. Such rotation will cause piston 42 to be projected in the manner shown in Fig. 3. Such projection will also cause the liquid to be expelled through passage 32 into the expandible member.

As that member increases in capacity it will extend for greater distances into the interior of tube 23. The latter being filled with gas under pressure it follows that the body of gas will be even further compressed. Accordingly the gas will act upon the outer face of the expandible assembly in an attempt to urge the liquid within the same back into the bores of cylinders 28 and 29.

The site of injection having been selected the orifice 20 of nozzle tip 19 is brought to a point overlying that site. That orifice may have a diameter of, for example, of .003" to .012". In any event, if the operator will shift pin 50 to a position at which its notch 51 is in line with the shoulder portion 54, shaft 52 may be rotated. With such rotation stem or plunger 53 will be retracted. Such retraction will occur either incident to the action of a spring such as 51, or because of the natural resiliency of block 60 and the parts of the assembly associated therewith. In any event, the edges of that block will not forcibly bear against the inner faces of the sleeve 62. Therefore, the expansive action on brake shoes 63 and 64 will be relieved. This will allow member 23 to project. The speed of projection will be controlled by the metering effect of the passages 31 and 32. In any event, plunger 12 will act against the base of the ampule and serve to expel medicament under pressures and at such velocities through the orifice 20 that the liquid will pierce the epidermis without it being necessary to employ a skin-penetrating needle.

According to the pressures employed the depth of penetration will be more or less. As afore brought out the operative pressure may be regulated by the amount of projection of rod 36 and its piston 33. When plunger 12 is fully projected, then piston assembly 35 will lie adjacent ring 41 or its equivalent which will function as a stop for the parts. Likewise the volume of the injected dosage may be varied by simply projecting screw threaded rod 44 to a greater or lesser extent. The amount of pressure and the volume of the dosage will be indicated through the slots 44 and 46. The desired results will at all times be achieved because of the interconnection provided as a consequence of the enclosure defined by the expandible member 26, the well portion 27, passages 31 and 32 and the position of the pistons within the cylinder bores 28 and 29. Piston 33 being unconnected to threaded rod 36, it may move anywhere within the range defined by the stops provided by the inner end of cylinder bore 28 and rod 36. On the other hand, piston 42 being connected to rod 44, it will positively shift in axial direction with that rod.

With the device discharged, rod 36 is fully retracted by applying to its portion 38 a suitable crank or wrench. Thereupon threaded rod or

shaft 44 is likewise turned to retract piston 42. The assembly of the latter contacting ring 41, body 24 and cylinder 23 will be positively retracted. Thereupon loading cap 21 will be dismounted, the spent ampule may be removed and discarded and a fresh ampule positioned within the medicament chamber. With the remounting of cap 21 the entire procedure may again be repeated with the operator adjusting screws 36 and 44 to precisely the positions which will assure an operating stroke and pressures such as are desired by the physician in attendance.

Thus among others, the several objects of the invention as specifically afore noted are achieved. Obviously numerous changes in construction and rearrangement of the parts might be resorted to without departing from the spirit of the invention as defined by the claims.

I claim:

1. A device for hypodermically injecting medicament including in combination a casing providing a medicament chamber adjacent one of its ends, a plunger projectible into said chamber for expelling the medicament therefrom, a pressure accumulator assembly within said casing operatively connected to said plunger to cause projection of the same, said assembly comprising a body containing gas under pressure, a member expandible into said body, a pair of liquid-containing cylinders connected to the interior of said member to expand the same, pistons movable one within each of said cylinders to displace liquid therefrom.

2. A device for hypodermically injecting medicament including in combination a casing providing a medicament chamber adjacent one of its ends, a plunger projectible into said chamber for expelling the medicament therefrom, a pressure accumulator assembly within said casing operatively connected to said plunger to cause projection of the same, said assembly comprising a body containing gas under pressure, a member expandible into said body, a pair of liquid-containing cylinders connected to the interior of said member to expand the same, pistons movable one within each of said cylinders to displace liquid therefrom and means for indicating the position assumed by said pistons within said cylinders.

3. A device for hypodermically injecting medicament including in combination a casing providing a medicament chamber adjacent one of its ends, a plunger projectible into said chamber for expelling the medicament therefrom, a pressure accumulator assembly within said casing operatively connected to said plunger to cause projection of the same, said assembly comprising a body containing gas under pressure, a member expandible into said body, a pair of liquid-containing cylinders connected to the interior of said member to expand the same, pistons movable one within each of said cylinders to displace liquid therefrom, means for indicating the position assumed by said pistons within said cylinders.

4. A device for hypodermically injecting medicament including in combination a casing providing a medicament chamber adjacent one of its ends, a plunger projectible into said chamber for expelling the medicament therefrom, a pressure accumulator assembly within said casing operatively connected to said plunger to cause projection of the same, said assembly comprising a body containing gas under pressure, a member expandible into said body, a pair of liquid-containing cylinders connected to the interior of said

member to expand the same, pistons movable one within each of said cylinders to displace liquid therefrom, means for indicating the position assumed by said pistons within said cylinders, and releasable lock means connected to said cylinders to restrain movements of the plunger.

5. A device for hypodermically injecting medicament including in combination a casing providing a medicament chamber adjacent one of its ends, a plunger projectible into said chamber for expelling the medicament therefrom, a pressure accumulator assembly within said casing operatively connected to said plunger to cause projection of the same, said assembly comprising a body containing gas under pressure, a member 15 expandible into said body, a pair of liquid-containing cylinders connected to the interior of said member to expand the same, pistons movable one within each of said cylinders to displace liquid therefrom, means for indicating the position assumed by said pistons within said cylinders, a further cylinder movable with said pair of cylinders, and expandible lock means disposed with said further cylinder to engage the bore of the same and prevent a movement of all of said cylinders and said plunger and means whereby said lock means may be freed from engaging the face of said bore.

6. A device for hypodermically injecting medicament including in combination a casing providing a medicament chamber adjacent one of its ends, a plunger projectible into said chamber for expelling the medicament therefrom, a tube connected to said plunger and adapted to have its interior filled with gas under pressure, a member connected to move with such tube, a member 30 expandible into said tube and mounted by said member, said first named member being formed with a pair of cylinders connected by passages with the space defined by said member and pistons disposed one within each of said cylinders for displacing liquid therefrom into the interior of said expandible member.

7. A device for hypodermically injecting medicament including in combination a casing providing a medicament chamber adjacent one of its ends, a plunger projectible into said chamber for expelling the medicament therefrom, a tube connected to said plunger and adapted to have its interior filled with gas under pressure, a member 45 connected to move with such tube, a member expandible into said tube and mounted by said member, said first named member being formed with a pair of cylinders connected by passages with the space defined by said member, pistons disposed one within each of said cylinders for displacing liquid therefrom into the interior of said expandible member, said body being formed with a further cylinder and releasable lock means extending into the bore of said further cylinder.

8. A device for hypodermically injecting medicament including in combination a casing providing a medicament chamber adjacent one of its ends, a plunger projectible into said chamber for expelling the medicament therefrom, a tube connected to said plunger and adapted to have its interior filled with gas under pressure, a member 60 connected to move with such tube, a member

expandible into said tube and mounted by said member, said first named member being formed with a pair of cylinders connected by passages with the space defined by said member, pistons disposed one within each of said cylinders for displacing liquid therefrom into the interior of said expandible member and means for individually projecting said pistons.

9. A device for hypodermically injecting medicament including in combination a casing providing a medicament chamber adjacent one of its ends, a plunger projectible into said chamber for expelling the medicament therefrom, a tube connected to said plunger and adapted to have its interior filled with gas under pressure, a member connected to move with such tube, a member expandible into said tube and mounted by said member, said first named member being formed with a pair of cylinders connected by 15 passages with the space defined by said member, pistons disposed one within each of said cylinders for displacing liquid therefrom into the interior of said expandible member, means for individually projecting said pistons and means associated with said projecting means for indicating the position assumed by each of said pistons within said cylinders.

10. A device for hypodermically injecting medicament including in combination a casing providing a medicament chamber adjacent one of its ends, a plunger projectible into said chamber for expelling the medicament therefrom, a tube connected to said plunger and adapted to have its interior filled with gas under pressure, a member connected to move with such tube, a member expandible into said tube and mounted by said member, said first named member being formed with a pair of cylinders connected by 20 passages with the space defined by said member, pistons disposed one within each of said cylinders for displacing liquid therefrom into the interior of said expandible member, means for individually projecting said pistons and means associated with said projecting means for indicating the position assumed by each of said pistons within said cylinders.
